MEANS FOR TRIMMING NONCIRCULAR CANS

Irvin L. Glerum, Chicago, Ill., assignor to Edwin I. Guthman & Co. Inc., Chicago, Ill., a corporation of Illinois

Application April 24, 1940, Serial No. 331,447

8 Claims. (Cl. 164—60)

This invention relates to means for trimming the ends of noncircular metal cans or pipes and particularly of cans having a generally rectangular cross section with rounded corners.

5 In many instances, it is desirable to have cans within which various elements may be disposed. These cans may have various cross sections. Thus in many radio receivers, cans having a rectangular cross section with rounded corners are quite frequently used. Such cans are generally drawn or extruded and then trimmed down to size. Since such cans must be handled by operators, it is necessary that the trimmed edges of the can be smooth and free of burrs.

10 15 Various methods of trimming such cans have been used with indifferent results. As a rule, the can is supported by dies, one on the inside and the other on the outside of the can to support the metal throughout its entire perimeter. Cans supported in this manner have been cut by a circular saw. However, this is relatively expensive and requires considerable up-keep of the saw.

20 25 Another method of trimming the cans involves the use of a straight cutter extending outwardly from a revolving shaft. The can, supported between dies, is fed toward the cutter with the plane of rotation of the cutter perpendicular to the axis of the can. Such a method is unsatisfactory for the reason that near the rounded corners burrs are formed which cut and tear the operators' fingers. The metal is also distorted, making removal from the dies difficult and making it impossible for subsequent use on automatic machines or other dies.

30 35 I have determined that the unsatisfactory operation of such a cutter is caused by excessive variation of the angle of attack between the cutting edge and the tangent to the surface of the can at the cutting point. Thus if the cutting tool is perpendicular to this tangent, a substantially pure cutting action results. This is true with a radial cutter operating on circular cans. However, if this angle varies, the force of the cutter on the can metal may be resolved into two components. One component, which may be called the cutting component, is parallel to the tangent to the can metal at the point of cutting. The other component is perpendicular to this cutting component, although in the plane of rotation of the cutter. This second perpendicular component cooperating with the dies holding the can metal results in a shear action.

40 45 50 55 60 It is evident that in shearing metal, there is some flow of metal and it is quite easy to determine from inspection of the sheared edge which way the shearing force is applied. If this shearing force is reversed so that at some part of the metal the shearing force is directed away

from the can interior and at other parts toward the can interior, the bending and flow of the metal along the sheared edge will be changed and burrs will result. This is true irrespective of how carefully the dies fit.

5 10 The action of a straight radial cutter on a can having a rectangular cross section results in an excessive variation of the shear force, the change in absolute value and sign of the shear component, considered as a vector, being so great that burrs result.

15 By the invention hereinafter disclosed, I have provided one means whereby the cutting angle is maintained at a substantially constant value. Another and preferred means is disclosed where- 15 in variation of the cutting angle is permitted but the cutting angle range is such that the shear component always retains the same algebraic sign. A cutter so designed to fulfill these conditions has been found to operate in a highly satis- 20 factory manner and trims the edges smoothly and quickly.

25 Referring to the drawing:

Figure 1 shows one form of the invention where a substantially constant cutting angle is maintained;

Fig. 2 shows a preferred modified form where- 25 in a curved cutter is used; and

Fig. 3 is a top view looking down upon Fig. 2.

30 Referring first to Fig. 1, a can 10 having straight sides 11 and rounded corners 12 and having a generally rectangular cross section is supported between an inside die 13 and an outside die 14, both dies fitting the can surfaces snugly. It is understood, of course, that both 35 dies are of a suitable length and mounted in a suitable manner so that the can may be moved lengthwise thereof from the cutter.

The end face of outer die 14 is provided with a cam groove 16 which substantially parallels the 40 outline of the can or pipe. Riding in this groove 16 are a pair of rollers 17 and 18 preferably close together and both rigidly fastened to a member 20 supporting a cutter 21 at one end thereof. The angle between the cutter and the can edge may 45 have any suitable value. It is understood of course that member 20 and rollers 17 and 18 are prevented from moving perpendicular to the plane of cutter rotation, here the plane of the paper, although free to travel around the groove. 50 A shaft 23 and rod 24 on the shaft furnish the motive power for pushing the cutter assembly along the groove.

The cam groove having a larger radius of curvature than the can edge permits the two 55 rollers to travel therein and maintain the cutter substantially at a constant angle to the can material. By feeding the can toward the cutter or vice versa, the ends may be trimmed off. It is understood of course that if the can has a dif- 60

ferent outline than rectangular that the groove will be similarly changed.

Referring to Figs. 2 and 3, a preferred form of this invention is shown. Here the can is mounted as before between dies. Inner die 13 may be eliminated, if desired, since the shearing force is directed toward outer die 14, as will be evident later. Cutter 30 having a spiral cutting edge 31 is provided. As shown in the original drawing, this cutter is drawn full scale and is adapted to operate upon cans whose sides are between one and one-eighth inches and two inches.

The cutter 30 may be rotated by a lathe spin-die or the like and part 14 may be held by a chuck as all that is necessary is to present the cutter to the work. Similarly, part 23 may also be revolved in the same way. The machine to hold parts 30 and 14 is omitted to simplify the 20 case.

The direction of rotation of this cutter—it is evident that in both forms the cutter may be stationary and the can rotated—is such that a stationary vector ending at the spiral would be elongated. For convenience this direction of rotation may be termed a spiral generating direction.

It will be noted that in this spiral, there is present a cutting component parallel to the tangent to the can material at the point of cutting and a shear component perpendicular to the tangent and always directed outwardly away from the can interior.

Almost any spiral shaped cutter may thus be used. It is only necessary that the spiral should have two points whose radius vectors are respectively small enough and large enough to accommodate the nearest and furthest points on the can. In a can having the cross section shown, 40 these points (assuming that the cutter center shaft is coincident with the can center) are one-half of the smallest side and diagonal respectively.

These two points on the cutter may have any 45 desired angular distance between them, the angle being measured vectorially.

The spiral as shown here is not necessarily a true mathematical spiral in the sense that it has a continuous mathematical equation. 50 While such a spiral may be used, it is easier to draw an arbitrary spiral between desired points. The curve of the cutter as disclosed here was obtained by merely using the curves on the so-called French curve used by draftsmen and consisting of a transparent solid having a large 55 number of differently shaped edges cut thereon.

It is preferred however to use outer edge 31 in the manner shown in Fig. 2 since the scrap may be more easily disposed of and does not 60 clog up the cutter.

It will be understood that by the term spiral generating direction is meant a spiral cutting edge revolving as disclosed in Fig. 2 so that the absolute value of the radius vector is increasing. 65

What is claimed is:

1. In a machine for trimming the ends of non-circular metal cans or pipes, the combination of means for holding such a non-circular can in cutting position, a cutter, means for moving said cutter relative to said can about an axis parallel to the length of the can and lying within the cross sectional area of the can, and means for maintaining the cutting angle substantially constant. 70

2. In a machine for trimming the ends of non-

circular metal cans or pipes, the combination of means for holding such a non-circular can in cutting position, a cutter, means for moving said cutter relative to said can about an axis parallel to the length of the can and lying within the cross sectional area of the can, and means for maintaining the cutting angle within predetermined limits sufficient to provide a smooth cut edge around the can. 5

3. In a machine for trimming the ends of non-circular metal cans or pipes, the combination of means for holding such a non-circular can in cutting position, a cutter, means for moving said cutter relative to said can about an axis parallel to the length of the can and lying within the cross sectional area of the can, and means for maintaining the cutting angle so that the force component perpendicular to the can surface at the point of cutting exerted by the cutting edge always points in the same general direction with reference to the can interior. 10

4. In a machine for trimming the ends of metal cans or pipes having a rectangular cross section, the combination of means for holding such a can in cutting position, a cutter, means for moving said cutter about an axis concentric with the axis of the can, and means for maintaining the cutting angle within such limits that the component perpendicular to the can surface at the point of cutting due to the force exerted 30 by the cutter always points in the same general direction with reference to the can center. 25

5. In a machine for trimming the ends of metal cans or pipes having a generally rectangular cross section, the combination of means for holding such a can in cutting position, a cutter having a predetermined angle to the can material for cutting the same, and means for moving said cutter relative to said can about the can axis, said can moving means including 35 a guiding member having substantially a congruent shape to said can cross section and controlling the cutter angle to maintain the same constant during its travel with respect to the 40 can. 45

6. In a machine for trimming the ends of metal cans or pipes having a substantially rectangular cross section, the combination of means including a die around the outer surface for holding such a can in cutting position, a cutter having a generally spiral cutting edge, and means for rotating said cutter about said can axis, said cutter having its cutting edge so disposed and the cutter being turned in such a direction that the shear component exerted by the 55 cutter upon the can is always directed outwardly from the interior of the can. 50

7. The combination of claim 6 wherein said cutting edge is on the outer leading side of the cutter and rotated in a spiral generating direction. 60

8. In a trimming machine, the combination of means for retaining a generally rectangular can or pipe in cutting position, and a cutter revolvable in a plane parallel to a can section and about an axis perpendicular to the can section and lying within the cross section thereof, said cutter having a generally spiral cutting edge of a curvature to maintain the shear component direction generally the same with respect to the can interior during a cutting cycle, said retaining means including a die along that can surface toward which the shear component points. 65
